RESONANT LINE

Nils E. Lindenblad, Port Jefferson, N. Y., assignor to Radio Corporation of America, a corporation of Delaware

Application January 4, 1937, Serial No. 118,971

13 Claims. (Cl. 178—44)

This invention relates to improvements in tuned circuits, and more particularly to such circuits known as resonant lines. Such lines usually comprise a pair of coupled concentric conductors which are employed for controlling the frequency of an electron discharge device oscillation generator, or wherever there is need for a parallel tuned circuit. Reference is herein made to the article by Clarence W. Hansell, entitled "Resonant lines for frequency control," published in Electrical Engineering for August, 1935, pages 852-856, and to the article by Clarence W. Hansell and Philip S. Carter entitled "Frequency control by low power factor line circuits," published in the Proceedings of the Institute of Radio Engineers, April, 1936, pages 957-969, and to United States Patents Nos. 2,077,800 and 2,108,895, granted April 20, 1937 and February 22, 1938, respectively, to Fred H. Kroger, for a more detailed description of the electrical properties and characteristics of these lines.

Heretofore, it has generally been the practice to use the resonant concentric line only with the extremely high frequencies, due mainly to the fact that the line has appreciable length and occupies much desirable space. Such lines, in many instances, may have a length approximately equal to one-quarter of the physical length of the operating wave. It will thus be seen that at a working wavelength of nine meters, for example, the length of the resonant line at a quarter wavelength is about seven feet. For relatively lower frequencies, however, the line becomes correspondingly longer and more cumbersome.

The present invention is designed to overcome the disadvantages of using long resonant lines and provides a shortened line resonator which is compact and occupies little space. It is thus possible to use the shortened resonant line of the invention at lower frequencies than heretofore deemed practical with previous types of resonant lines.

In brief, the shortened resonant line of the invention comprises a line which is folded concentrically instead of continuing in a straight line, as heretofore. A more detailed description of the invention follows in conjunction with the drawing wherein Figs. 1 and 2 illustrate two different embodiments of folded resonant lines in accordance with the invention.

Referring to Fig. 1 in more detail, there is shown a resonant line comprising an outer cylindrical conductor 10, an inner conductor 14 at the center, and intermediate cylindrical conductors 11, 12 and 13. Cylindrical conductors 11 and 13

are connected to one base 15 of the line and conductors 12 and 14 are connected to the base 16 of the line to form folds, for simulating a continuous line. To obtain a uniform line effect, that is, substantially uniformly distributed inductance and capacity throughout the folded line, the diametrical ratios of the folded sections of the line as measured from the longitudinal axis of the line, are made to be the same. In other words, the ratio of the diametrical distances 10

$$\frac{a}{b}$$

is made equal to the ratio of the distances 15

$$\frac{c}{d}$$

and to equal the ratio of the distances 20

$$\frac{e}{f}$$

or

$$\frac{a}{b} = \frac{c}{d} = \frac{e}{f}$$

The diametrical distance b differs from c by the thickness of the material of the cylindrical wall 11 and similarly d differs from e by the thickness of the material of the cylindrical wall 12. If desired, the uniform line effect may be departed from and a concentrated or lumped reactance effect obtained by changing the diametrical ratios, especially if it is desired to still further reduce the total length of the resonant line. A decreased diametrical ratio will give an increased capacity per unit length of line. In this manner the folding up feature may be combined with the provision of a lumped capacity, and where this is effected, it is preferred that it be done at the free end of the line, i. e., at the last section where the diametrical ratio between inner conductor 14 and cylindrical wall 13 may be made smaller than the ratios between the other adjacent concentric surfaces. Thus, there can be obtained two degrees of freedom or two tuning points, a mode of operation seldom desired, except in filter circuits. 45

In the line of Fig. 1, the current is largest at the base of the line 15 where the incoming feeder 17 is connected to the cylindrical wall 11. Consequently, it is at this point that there is provided the largest cross section in order to give the 50 smallest resistance effect. Since the high voltage point is developed between the innermost conductor 14 and its adjacent cylindrical conductor 13, and the spacing therebetween is the smallest, the precaution must be observed that the voltage 55

gradient between these conductors be not too high. For certain spacings between the innermost conductor 14 and its adjacent conductor 13, there will be found to be certain limiting voltage values.

Where concentrated reactance (lumped capacity) effects are not present, such as may be due to a difference in diametrical ratios of the conductors, as mentioned above, it is preferred that the total length of the folded concentric resonant line of Fig. 1 be approximately one-quarter the length of the communication wave; that is, the sum of the lengths of conductors 11, 12, 13 and 14, as measured from their respective bases 15 or 16 to which they are connected to their open ends, should be approximately one-quarter the length of the operating wave.

The resonant line of Fig. 1 is herein shown as a frequency control line for the electron discharge device vacuum tube oscillator circuit connected to lead 17. This external circuit, however, is merely given for the purpose of illustration and is not to be construed as being limitative of the invention since the line may be used in other capacities, and other modes of coupling thereto may be provided. For example, instead of the direct coupling over lead 17 we may provide capacitive coupling to the line at points of higher voltage, of which the free end of each fold is the extreme. Two such methods of capacitive coupling comprise condenser 18 and conductor 19, shown in dotted lines connected to the free end of inner conductor 14, and condenser 20 and lead 21 shown in dotted lines connected to the free end of conductor 13. Similarly, where desired, magnetic coupling may be employed, such as shown by dotted loops 22 and 23 which are connected near the outside of and close to the base of a fold where there is a large or relatively strong magnetic field. Thus, for example, where conductors 10 and 11 make one fold, the loop 23 is located correctly nearest the smaller conductor 11 and at the base of the fold. It is preferred that the magnetic coupling obtained by loops 22 and 23 be nearest the greatest flow of current within each space for each section in order to obtain close coupling. This effect of close coupling is greatest at the place where the field gradient is greatest, and such a location will be near the smallest diameter wall of each section. A looser magnetic coupling may, of course, be obtained by coupling a loop at places other than that shown by loops 22 and 23, such as at 24. It will thus be seen that there may be provided either conductive, capacitive, or magnetic coupling, and various degrees of coupling. These methods of coupling enable the line to be used for many purposes, not only as a frequency control line for an oscillator, but also as a combined tank circuit and coupling unit between stages. For example, if it is desired to employ the resonant line of Fig. 1 as a coupling circuit between stages, loop 22 can be connected to the output of one stage, and loop 23 connected to the input of the succeeding stage.

The arrows in Fig. 1 of the drawing indicate the direction of the flow of current, and it will be seen that the shell current in one section becomes the center conductor current in the next section. Fig. 2 shows an alternative folded resonant line in accordance with the invention, where the next outermost cylindrical conductor 23 forms the high voltage end of the line, and the centermost conductor 24 the high current end. In other words, the outside of plate 25 would have the highest voltage of the resonant line. This condition is

just the opposite of what is found in the line shown in Fig. 1. We thus have, in Fig. 2, a high voltage end at the largest diameter section and a high current end at the smallest diameter section. The external circuit may be coupled either conductively, magnetically, or capacitively to the resonant line of Fig. 2 in a manner somewhat similar to that shown in Fig. 1; that is, the capacitive coupling may be effected at points of high voltage, whereas the magnetic coupling may be effected at points of greatest current flow.

It will be understood, of course, that the invention is not limited to the precise arrangements shown in Figs. 1 and 2, since various modifications may be made without departing from the spirit and scope of the appended claims. For example, the conductors of the folded resonant line of the invention may be tapered to give the same constant ratio between the center and the shell of the conductors as mentioned above in connection with Fig. 1. The larger diameters can then be used as a high current end of the line. In this case, of course, the amount of taper will naturally be limited by the corona limit at the high voltage end in the event that extremely high voltages are used.

What is claimed is:

1. A folded, resonant line comprising an outer conductor and a concentric central conductor electrically coupled together at one end, and an intermediate concentric conductor constructed and arranged to be electrically coupled to said outer conductor at its other end, said intermediate conductor extending substantially parallel to said central conductor for the greater portions of the lengths of the last two conductors, the sum of the lengths of said central and intermediate conductors having a predetermined relation to the wavelength of oscillation of said resonant line.

2. A folded, concentric resonant line comprising an outer cylindrical conductor and a central conductor, a mechanical and electrical connection between said conductors at one of their adjacent ends, and an intermediate cylindrical conductor constructed and arranged to be mechanically and electrically coupled to the other end of said outer conductor, said intermediate conductor extending parallel to said central conductor for the greater portions of the lengths of the last two conductors, the sum of the lengths of said central and intermediate conductors having a predetermined relation to the wavelength of oscillation of said resonant line.

3. A folded, concentric resonant line comprising an outer conductor, an inner central conductor, and a plurality of intermediate concentric conductors parallel and surrounding the greater part of the length of said central conductor, adjacent ones of said intermediate conductors being so constructed and arranged as to be conductively connected at one of their respective ends to opposite ends of said outer conductor, the other ends of said intermediate conductors being free, alternately located ones of said conductors within said outer conductor being connected to the same end of said outer conductor.

4. A resonant line in accordance with claim 3, characterized in this that said outer and inner conductors are cylindrical.

5. A folded, concentric resonant line comprising an outer conductor, an inner central conductor, and a plurality of intermediate concentric conductors located within said outer conductor and between said outer conductor and said central conductor, adjacent ones of all of said inner

- conductors being connected at one of their respective ends to opposite ends of said outer conductor, the other ends of said inner conductors being free, alternately located ones of said inner conductors 5 being connected to the same end of said outer conductor, said intermediate conductors being so arranged that the diametrical ratio measured from the longitudinal axis of said resonant line to any two adjacent surfaces of adjacent conductors is the same throughout said line.
6. In combination, a resonant line comprising an outer conductor and a concentric central conductor electrically coupled together at one end, an intermediate concentric conductor constructed 10 and arranged to be electrically coupled to said outer conductor at its other end, and a utilization circuit conductively coupled to said intermediate conductor in the interior of said resonant line at a location where there is substantially 15 the greatest flow of current in said line.
7. In combination, a folded, concentric, resonant line comprising an outer cylindrical conductor and a central conductor, a mechanical and electrical connection between said conductors at 20 one of their adjacent ends, an intermediate cylindrical conductor constructed and arranged to be mechanically and electrically coupled to the other end of said outer conductor, and a utilization circuit conductively coupled to a point of low potential 25 on said line.
8. In combination, a resonant line comprising an outer conductor and a concentric central conductor electrically coupled together at one end, an intermediate, inner, concentric conductor electrically coupled to said outer conductor at its other end, and a utilization circuit conductively coupled to said intermediate conductor at a location 30 near the junction of said intermediate conductor with said outer conductor, the sum of the lengths of said inner conductors being approximately one-quarter of the length of the wave to whose frequency the line is resonant.
9. A folded, concentric resonant line comprising an outer conductor, an inner central conductor, and a plurality of intermediate, inner, concentric conductors, adjacent ones of said inner conductors being connected at one of their respective ends to opposite ends of said outer con- 35

ductor, the other ends of said inner conductors being free, alternately located ones of said inner conductors being connected to the same end of said outer conductor, the sum of the lengths of all of said inner conductors being approximately one-quarter of the length of the wave to whose frequency the line is resonant. 5

10. In combination, a resonant line comprising an outer conductor and a concentric central conductor electrically coupled together at one end, 10 an intermediate inner concentric conductor electrically coupled to said outer conductor at its other end, the sum of the lengths of all of said inner conductors being approximately one-quarter of the length of the wave to whose frequency 15 the line is resonant.

11. A folded resonant line comprising an outer conductor and a concentric central conductor electrically coupled together at one end, and an intermediate concentric conductor electrically 20 coupled to said outer conductor at its other end, said intermediate conductor being so constructed and arranged that the diametrical ratio measured from the longitudinal axis of said resonant line to any two adjacent surfaces of adjacent conductors is the same throughout said line. 25

12. A resonant line comprising an outer conductor and a concentric central conductor electrically coupled together at one end, an intermediate concentric conductor electrically coupled 30 to one of said first two conductors at its other end, said intermediate conductor being so constructed and arranged that the diametrical ratio measured from the longitudinal axis of said line to any two adjacent surfaces of adjacent conductors is the same throughout said line. 35

13. A compact concentric resonant line comprising an outer cylindrical conductor and a central conductor, a mechanical and electrical connection between said conductors at one of their adjacent ends, an intermediate cylindrical conductor constructed and arranged to be mechanically and electrically coupled to the other end of said outer conductor, the sum of the lengths of said central and intermediate conductors being 40 related to the wavelength of oscillation of said resonant line. 45
